UNITED STATES PATENT OFFICE.

CHARLES S. WILLIAMSON, OF CHICAGO, ILLINOIS.

MEANS FOR HANDLING COAL.

1,177,751

Specification of Letters Patent.

Patented Apr. 4, 1916.

Application filed August 9, 1911. Serial No. 643,192.

To all whom it may concern:

Be it known that I, CHARLES S. WILLIAMSON, a citizen of the United States, residing at Chicago, county of Cook, State of Illinois, have invented certain new and useful Improvements in Means for Handling Coal, of which the following is a specification.

The present invention has as one of its objects the provision of a dock construction and an unloading mechanism whereby boat-loads of coal, may be transferred to a dock for storage or for reshipment. The invention also provides for the simultaneous unloading of more than one boat and for the redistribution of the unloaded material into cars without confusion of material and without inconvenience in the handling of the loaded or unloaded cars. A part of the dockage may be devoted to the handling and storage of anthracite coal and a second part to the handling and storage of bituminous coal and the relative proportions of the dockage thus assigned may be changed easily and without radical additions or alterations in the coal handling machinery, thereby giving to the system as a whole a certain flexibility and adaptability not ordinarily found in coal handling docks.

It is a further object of the present invention to arrange the railway car tracks in convenient position for loading with either anthracite or bituminous coal and to provide a special arrangement and construction of screening and sorting devices whereby this loading may be accomplished with despatch and with the minimum of handling.

As is well known, bituminous coal may be stored in bulk in the open air, but anthracite coal requires for its protection a weather-proof covering or shed. According to the present invention the anthracite shed is so constructed in its various details that the anthracite coal can be unloaded from a boat and then graded and distributed according to size or reloaded into cars for reshipment, all with a minimum of time and trouble.

Also this shed may be so constructed as to admit of ready enlargement over the yard initially assigned to bituminous storage without rearrangement of the screening plant, belt conveyer and other essential features of an anthracite storage plant. In furtherance of the general objects above set forth the movable bridges which span the bituminous yard are equipped with storage

hoppers arranged in a special way for the easy grading and redistribution of coal throughout any part of the yard and from any part of a boat without interference in any way with the continuous operation of the anthracite plant and without disturbance to the boat lying alongside the anthracite shed.

The objects above enumerated and others of a similar nature are accomplished by the specific embodiment disclosed in the accompanying drawing and hereinafter described in detail.

In the construction shown, the dockage has two water fronts, each capable of accommodating a modern coal boat, and each provided with its own unloading machinery. Coal from one boat is hoisted by a suitable bucket and then may be deposited in cars either with or without screening or it may be carried along a bridge structure and deposited in an open storage yard. The bridge structure is movable along the dock on suitable tracks to secure uniformity in the distribution of the stored coal. A second or duplicate bridge may also be provided for this same storage yard. But while this unloading is going on, a second boat can be drawn up to the end of the dockage and its coal there taken out by another bucket system and then deposited within a storage shed. Or if desired, the coal can be transferred to a suitable screening plant and then delivered to railway cars at the side of the shed for shipment. Each boat can be shifted along its own dockage to effect complete unloading without interfering with the other boat and the railway cars can be shunted in and out to receive their various kinds of coal all without interference.

The details of my invention will be better understood by reference to the accompanying drawings wherein—

Figure 1, is a plan of the complete coal hauling system. Fig. 1^a, is a detail of the tilting box car loader and its co-operating "kick back" used at the side of the anthracite shed. Fig. 2, is a side elevation of one of the bituminous bridges with the center of the bridge broken away. Fig. 3, is an end elevation of the bridge from the water side. Fig. 4, is a similar elevation from the opposite end of the bridge. Fig. 5, is a sectional elevation through the anthracite shed. Fig. 6, is a side elevation of the anthracite shed and its co-operating unloading tower. Fig.

7, shows a modified form of trolley-way for the anthracite shed. Fig. 8, is a plan of the shed. Fig. 9, is an end elevation of the shed, and Fig. 10, is a side elevation thereof.

5 According to the general arrangement of apparatus and the general scheme of operation illustrated in the accompanying drawings, bituminous coal is carried in a boat 1 of modern construction into the slip or 70 waterway which extends along one of the long sides of the dock property. The coal is taken out of the hold of this ship by means of the coal-handling bridge 2, movable for a part of the length of the dock 75 property on its own tracks and equipped with a suitable man-trolley and an automatic grab-bucket, whereby the coal may be raised through the hatches of the boat and then delivered either to the storage yard of the 80 dock, or to suitable hoppers provided for loading the coal into cars, as hereinafter described more at length. Simultaneously with the unloading of bituminous coal from the slip side of the dock, a second boat 3 85 may be drawn up at the channel end of the property and there unloaded through the agency of an unloading tower 4, movable crosswise of the dock property and equipped with grab-bucket operated from a man- 90 trolley and capable of delivering the coal from the boat either to the storage area of a shed or shelter, or to a hopper from which it may be subsequently loaded into railway cars. Each of the boats can be unloaded 95 and its contents screened, sorted or deposited for storage, all without interference between the boats or their unloading mechanisms. Simultaneously, or subsequently, to the unloading of the boats, the coal may be 100 loaded into railway box cars for shipment without complications in the switching arrangements and without objectionable delays for the shunting of cars. Furthermore, the system as a whole presents a certain 105 flexibility or adaptability whereby the size of the anthracite shed may be increased even to substantially double its initial capacity, without interfering with the general lay-out and without any alteration in the means 110 whereby the coal is hoisted, transported, graded and delivered.

115 The traveling bridges, whereby the bituminous coal is unloaded from boat 1, are duplicates in all regards and hence only one of them need be described in this specification. The bridge span is sufficient to extend substantially across the dock property and has a folding apron or extension arranged to project over the hatches of the boat. The 120 bridge span is supported by two towers. The supporting tower 5 on the water side (of the steel rocker bent or sheer leg type) is flexibly connected to the bridge span in such a way as to provide for minor inequalities of gage between the

tracks 6 on the rear of the dock and those 7 on the front of the dock. The supporting tower 8 on the rear of the bridge is of V-leg construction and is especially designed to provide ample strength for endwise wind 70 loads upon the bridge and for the end thrust induced in the structure by the acceleration and retardation of the man-trolley. The entire bridge structure and its two towers are flexibly related so that the span shall rest 75 upon both the V-leg and the sheer leg in such a way that either end may be advanced ahead of the other end to an angle of about six degrees on either side of a line through the center of the other supporting tower at 80 right angles to the rails upon which these towers travel. This is accomplished by connecting the span to its supporting towers at their lines of centers by means of kingpins, all connections being such as to provide for rotation about these king-pins to the amount named. By this arrangement, one end of the bridge may advance or fall behind the other end without introducing 85 stresses detrimental to the structure. The 90 bridge is carried on 32 rolled steel wheels, sixteen wheels under the sheer leg and an equal number under the V-leg. These wheels are arranged in clusters of eight 95 under the four corners of the bridge and these eight wheels are mounted in compensating trucks to insure equalization of the weight brought to each corner of the structure. The load is brought to the journals 100 of these wheels through the agency of an equalizing plate girder 9 pin-connected to the box girder 10, which in turn is pin-connected to the supporting tower. Motors 12 are provided for propelling the bridge along its tracks, these motors being connected 105 for driving all the supporting wheels of the bridge. The 2 motors which pertain to the sheer leg will be operated through the controller nearer this leg, while the 2 motors which pertain to the V-leg will 110 be controlled through the agency of the controller toward that leg. The location of these controllers is such that the operator may move the bridge with one controller 115 handle in each hand, thereby allowing him to move either end independently of the other or to move both ends simultaneously.

An apron 13 is hinged on the bridge structure and is arranged to extend out over the boat for the purpose of unloading the 120 coal. The apron is stiffened and braced against side wind, and the weight of its outer end is carried into the bridge structure through folding I-bars 14 pin-connected at their lower end to suitable yokes in 125 the apron and at their upper end to a mast 15 built into the bridge structure. The construction of this apron and mast is such as to provide for the easy raising and lowering 130 of the outer end of the apron to allow

the masts of vessels a free path in the slip. The apron is raised about its hinged point 16 as a fulcrum through the agency of two independent equalized sets of plow steel cables which lead from the top of the mast around suitable sheaves 17 in the outer end of the apron and are carried to a suitable winding drum in a house 18 mounted on the bridge span. The trolley 19 which operates on this bridge runs on steel rails riveted to I-beam girders. The trolley run-way terminates in the outer end of the apron and is there provided with an automatic terminal buffer 20 of any well-known kind capable of gradually applying an increasing force tending to retard the motion of the trolley. This buffer applies its retarding effect directly to the treads of the wheels and is so adjusted as to bring the trolley to rest without undue shock. In addition to this buffer the ends of the rails are turned up at 21 to a height greater than the radius of the track wheels and are so backed up by rigid gusset plates 21' as to prevent the trolley from running off the run-way under any condition of failure of buffers and brakes.

The hoisting means may comprise a grab bucket 22 of the clam shell variety operated in the usual manner from a cab 23.

On the water side of the bridge a protecting canopy 24 is suspended from the truss to cover the first 2 car tracks beneath the path of the clam shell when unloading coal from a boat. At the other end of the bridge the V-leg is provided with a 50 ton hopper 25 the bottom of which is provided with suitable feeder gate mechanism for delivering coal at a rate suitable for supplying a Christy box car loader 26 mounted beneath the hopper and traveling with the bridge along the bridge track. Above the V-leg of the bridge is a sheet metal canopy 27 of sufficient length to cover and protect the machinery parts of the trolley while it is standing at this point during periods of idleness.

A bituminous screening plant 28 is mounted on track wheels 29, distributed at the corners of compensating tandem trucks. This screening plant operates on "service tracks" of about 12 foot gage located between the rail road tracks and the sheer leg of the bridge. The screening plant is self-propelled by any well-known mechanism at a speed about equal to that of the bituminous bridge. "Run of pile" coal is delivered either from the boat or from the dock to a 50 ton hopper and from there the coal passes through suitable feeder mechanism to screens and other agencies whereby some of the coal may be delivered to a railway car and the remainder may be sorted or graded and disposed of in a suitable manner. Since the screening plant is self-propelled and

movable on its own service tracks, it may be adjusted under either the bridge 2 or its companion bridge. Coal taken from the boat may be delivered to the movable screening plant on the slip side of the dock and there resized into the various grades of coal desired, a part of the products being delivered to cars and the balance to the dock, or in lieu of this, the coal taken from the boat may be carried across the bridge to the 50 ton hopper and there delivered directly to cars without change in its sizing. Ordinarily the screening operation is applied to domestic coal and the direct handling is applied to railroad coal.

The rail road track arrangement on the water side of the dock comprises 2 complete track ways 30 and 31 extending the full length of the bituminous storage yard and having an extension 32 which overlaps or runs along the water side of the anthracite shed to the end of the dock. A cross-over 33 and a double cross-over 34 are provided for the ready shunting of empty and loaded cars. A cable haul plant 35 may also be installed along the water front for carrying out the necessary shunting operations. On the opposite or rear side of the dockage the track arrangement includes 3 parallel ways 36, 37 and 38 with cross-overs 39, 40 and 41 arranged as shown in the drawings and with a car haul 42 located at the side of the anthracite shed and at the extreme end of the dockage. On the track 36 nearest to the shed is a mechanical box car loader 36a, as for instance of the tilting type, and at this point the track elevation is high enough to give to a loaded car considerable momentum when it is shunted or pushed from the loader toward the end of the dock. From the loader, the track runs downward as shown in Fig. 1^a but the ends of the track are curved upward to form a "kick back" 36^a, upon which the loaded car may run, and from which the car is thrown backward through the switches and cross-over to one of the adjacent tracks. By thus automatically delivering the loaded cars one at a time on a track remote from the side of the shed, the switching or car hauling operations are greatly facilitated.

The anthracite shed comprises a main structure or covering carried on columns 43 with a lean-to roof 44 over the houses on the side toward the end of the dock. There are a plurality of (see Fig. 5) main bays running parallel with the slip of the dock and each bay carries two runways 45 and 46 for a suitable man trolley. The roof trusses 47 are of structural steel shapes and plates and span the entire distance between adjacent columns and carry the roofing, which may be of sheet metal. There are a plurality of openings 48 in the end of the building adjacent to the end of the dock. These open-

ings are provided to receive the man-trolley and extend from the runway level downward in a vertical line to the junction line of the lean-to roof, and from this point in an inclined 5 direction to a point ten feet above the junction of the end bulk head with the inclined roof. Shingle hatch plates or other suitable well known closures may be used to close these openings when the shed is being filled. A 10 suitable girder 49 is built into the structural framing of the shed on the end adjacent to the end of the dock for the purpose of carrying the end of the anthracite unloader 4. This girder is designed not only to take the 15 vertical loads induced in the structure by the operation of the trolley, but also to take the endwise thrusts brought about by accelerating and retarding the same. On three sides of the shed, namely, the two sides 20 50 and 51, parallel with the slip, and the side adjacent to the end of the dock, a curtain wall 52 of reinforced concrete is installed, this wall being self-sustaining and being carried on the same footing as the steel columns 25 which form the side framing of the building. The bulk head on the side 53, adjacent to the bituminous coal storage, is made of timber and is so constructed that it may be easily taken down for moving when the capacity of 30 the anthracite shed is to be increased. In other words, it may be regarded as a temporary closure for that end of the shed.

A belt conveyer 54 extends along the rear 35 end of the anthracite shed in such position that it may be used for carrying the anthracite coal from the man-trolley to the "loading out" screening plant 55. A traveling hopper 56 is mounted above this belt conveyer and is movable thereover and can be 40 placed to register with any of the various runways of the shed.

The anthracite unloading tower 4 is used 45 for taking coal from a boat 3, lying along the channel end of the slip and delivering the same to storage area within the shed, or to the belt conveyer for loading out directly. This loader is equipped with a man-trolley 50 57, operating a grab-bucket 58, this trolley and bucket being duplicates of those used on the bituminous coal-handling bridges. The tower structure consists of a sheer leg 59 extending from the dock level and pin-connected to the bridge structure which carries the trolley. This pin connection provides for minor motions of the face of the dock with respect to the anthracite shed, all 55 endwise thrusts from the trolley and wind being transferred to the frame of the shed. The apron structure, which extends out over 60 the boats, corresponds in size and type of construction with that used on the bituminous bridges. The sheer leg 59 of the unloading tower is equipped with trucks 60, which may be four wheel trucks, fully compensated 65 to equalize the load on the wheels under

each corner, each truck having an electric motor mounted thereon and driven thereby. The end of the unloader, which travels on the anthracite shed, is equipped with two trucks 61, which may be two wheel trucks, 70 and in addition, suitable horizontal trucks are provided for transferring the endwise thrust of the structure into the framing of the anthracite shed. Even though the unloading tower is movable across the face of 75 the dock and, in a certain sense, is independent of the shed structure, nevertheless that structure properly may be regarded as an integral part of the unloader, coöperating therewith in the support and travel of the man-trolley and 80 its load of coal. It is as if a portion of the unloader were roofed over to protect the stored coal, with the additional feature that a temporary end or bulk head can be removed at the back of the shed to increase the 85 effective length of the storage capacity for anthracite without otherwise influencing other features of the anthracite plant.

The roof of the anthracite shed is carried on vertical columns or steel structures and 90 each of these columns carries at its top and separate from the roof, a runway for the man-trolley of the bridge, this runway being suspended from a cantaliver carried at the top of the column. In the structure 95 shown in Fig. 5, each runway comprises two I-beams each secured at the lower end of a diagonal member 63 which depends from the horizontal girder 64, the latter being arranged and braced as shown in the drawing. 100

Fig. 7 shows a modified type of cantaliver suspension wherein the runway consists of but a single rail 65. With a monorail runway as above described, the man-trolley is slung in a suitable hanger which need not 105 here be described.

In this specification the means for transporting the grab-bucket has been referred to as a man-trolley, and has been illustrated as such. However, it will be understood that 110 other forms of trolley may be used without departing from the basic principles of my invention.

The electrical wiring for the dock includes a source of current comprising a protected rail 66 carried on a line of posts, placed between the screening plant rails and the sheer leg of the bituminous bridges. With this arrangement, the bridges can receive current from one pair of feeders on 115 one side of the line of posts and the box car loaders and bituminous screening plant may take current from the other side of the line of posts. This arrangement gives a compact electrical system, while at the same 120 time insuring extreme flexibility in the manipulation of either the bituminous bridge or the screening plant, or the box car loader.

Although I have above described a com- 125 130

plete plant embodying the novel features of my present invention, I have not deemed it necessary, to an understanding of the features herein claimed, that all details of the system should be shown in the drawing, or mentioned in the description. These details are built in accordance with approved engineering practice and may be varied in many ways without changing, in a radical way, the basic and underlying principles of the complete system or structure.

What I claim as new and desire to secure by Letters Patent of the United States is:

1. A construction suitable for handling coal or other material, said construction comprising, in combination, a movable bridge, coil-hoisting means carried by said bridge and including a grab bucket trolley, a shed carrying a track on which one end of said bridge runs, said shed having a roof and columns supporting said roof, each of said columns carrying at either side at least one rail supported from said column on a cantaliver and adapted to serve as a runway for the grab bucket-trolley and its load of coal.

2. A construction suitable for handling coal or other material, said construction comprising, in combination, a tower bridge movable along a water-front and carrying coal-hoisting means including a grab bucket-trolley, a shed adjacent to said tower bridge and having a roof and a plurality of columns, a plurality of runways supported from cantalivers on said columns with each

of which said movable tower bridge may be placed in alinement, said runways being independent of said roof and being intersected near the back of the shed by a belt conveyer, and a hopper movable over said belt conveyer and into alinement with any of said runways.

3. A construction suitable for handling coal, said construction comprising, in combination, a plurality of railroad tracks parallel with a water-front of the dockage, said tracks being spaced apart to form therebetween a storage yard for coal, a storage shed facing a second water-front arranged at substantially a right angle to the water-front first mentioned, said storage shed being lapped at either side by said railroad tracks, a plurality of companion traveling bridges having coal handling machinery thereon, spanning said storage yard, a tower bridge movable across the end of the dockage and carrying coal hoisting means including a grab bucket trolley movable into said shed to deliver coal therein, the back of said shed being of temporary construction to facilitate reapportionment of the dockage devoted to different kinds of coal, service tracks between the railroad tracks and the water ends of the bridges substantially described.

In witness whereof, I hereunto subscribe my name this 5th day of August, A. D. 1911.

CHARLES S. WILLIAMSON.
